UNITED STATES PATENT OFFICE

FRANK LICHER, OF ATTLEBORO, MASSACHUSETTS, ASSIGNOR, BY MESNE ASSIGNMENTS, TO FRANK S. LAND, OF KANSAS CITY, MISSOURI

DESIGN FOR A BROOCH

Application filed March 28, 1933. Serial No. 47,616. Term of patent 14 years.

To all whom it may concern:

Be it known that I, FRANK LICHER, a citizen of the United States, residing at Attleboro, in the county of Bristol and State of Massachusetts, have invented a new, original, and ornamental Design for Brooches, of which the following is a specification, reference being had to the accompanying drawing forming part thereof.

Fig. 1 is a front elevation of a brooch, showing my new design.

Fig. 2 is a side elevation of the same.

I claim:

The ornamental design for a brooch, as shown.

FRANK LICHER.
